UNITED STATES PATENT OFFICE.

FERGUS F. WILSON, OF BROOKLYN, NEW YORK, ASSIGNOR TO MERGENTHALER LINOTYPE COMPANY, A CORPORATION OF NEW YORK.

PRINTING BAR OR SLUG.

1,079,086.

Specification of Letters Patent. Patented Nov. 18, 1913.

Application filed April 27, 1912. Serial No. 693,602.

To all whom it may concern:

Be it known that I, FERGUS F. WILSON, a citizen of the United States, and a resident of Brooklyn, county of Kings, and State of New York, have invented a new and useful Improvement in Printing Bars or Slugs, of which the following is a specification.

My invention relates to printing bars or slugs, such as linotypes, comprising a body formed with printing characters thereon.

More particularly, it refers to bars of the kind provided with overhanging portions carrying the printing characters, which portions normally project over and rest upon adjoining slugs or bars.

Still more specifically, it relates to such slugs or linotypes as are intended for use in the production of ruled or tabular work. Such ruled work may be produced from linotypes or slugs in several different ways. For instance, and particularly where transverse lines are desired to give the effect of tables, and the like, the slugs are frequently formed with notches extending below the printing edge and into the body portion. These cuts or notches are located so as to register when the slugs are set into a form, and in the continuous channel or groove thus produced are inserted "rules", which form the desired lines.

It is one of the purposes of my invention to dispense with the use of these rules, and to that end I propose to employ bars or slugs, one of which is formed with groups of ordinary type characters, having suitable spaces between them, and the other with overhanging portions formed with ruling characters, which portions project into the spaces between the groups of characters on the other slug, and are supported thereby.

The result of this arrangement is that a line is printed with groups of characters, between which the transverse lines appear. Such pairs of bars may be combined to any extent desired, and their transverse lines caused to register, so that the general effect of continuous transverse lines will be secured therefrom. Obviously, such pairs of slugs, either singly or in combination, are available and useful for many purposes, such as baseball scores, railway time tables, various forms of advertising matter, and the like. To secure these results, I preferably form the ordinary slug of the usual thickness, and the coöperating slug with a more reduced or thinner body, which construction of the lat-

ter slug is rendered possible by the fact that its main purpose is to provide the projecting ruling characters, which are supported by the other slug in ordinary use. This arrangement also permits me to obtain other necessary or ornamental features, such for instance as the provision of a continuous edge on the body of the tabular slug, which will form an unbroken longitudinal line, while the ruling characters on the overhanging portions form the transverse lines, in the manner previously described. In order to give the overhanging portions greater rigidity, I preferably form strengthening elements thereunder, which elements project from the side of the slug and below the edge thereof.

In the accompanying drawing, I have shown my invention in preferred form and by way of example, but obviously many variations and modifications may be made therein without departing from its spirit.

Generally speaking, I desire it to be understood that I do not limit myself to any particular form or embodiment, except in so far as such limitations are specified in the claims.

Referring to the drawing: Figure 1 illustrates a specimen of printed matter, such as may be secured in the use of my improved slugs; Fig. 2 is a perspective view of the two cooperating slugs, slightly removed from each other; and Fig. 3 is a sectional view thereof, on an enlarged scale, taken substantially on the line 3—3 in Fig. 2.

The slug A is provided in the usual manner with printing characters A¹, which characters are suitably grouped and spaced for tabular work. The slug B is much thinner and is formed with overhanging portions B¹, which portions are so located as to fit into the spaces between the groups of characters A¹ on the slug A, it being noted that when the two slugs are in operative relation the overhanging portions B¹ will be firmly supported by the slug A. The slug B is preferably formed with transverse ruling characters B² located upon the overhanging portions B¹, so that when a print is taken from the combined slugs transverse vertical lines will appear between the characters. The slug B may be formed with additional printing characters if desired, such as the longitudinal line B³.

When the pairs of slugs are assembled to

constitute a printing surface or "form", the print therefrom will be substantially that indicated in Fig. 1, wherein the characters a^1 are produced by the type A^1 on the slug 5 A, the transverse lines b^2 by the ruling characters B^2 on the overhanging portions B^1 of the slug B, and the unbroken line b^3 by the printing edge B^3 on the slug B. Obviously, by causing the ruling characters B^2 on the 10 several slugs to register in the well known manner, substantially continuous vertical lines are secured.

In view of the fact that the overhanging portions B^1 of the slug B, when in operative printing position, are supported by the slug A, I am enabled to form an extremely reduced or thin body for the slug B, as compared with that of the slug A. In order to strengthen and give firm support to the overhanging portions B^1 of the slug B, I preferably form the latter with a reinforcing element B^4 below the portion B^1 , projecting from the side of the slug B and below its edge, as shown in Fig. 3.

As already stated, I have shown my invention in preferred form and by way of example, but obviously many variations and alterations therein will suggest themselves to those skilled in the art and still be comprised within its scope.

Having thus described my invention, its construction and mode of operation, what

I claim and desire to secure by Letters Patent of the United States is as follows:

1. A tabular slug comprising a body portion formed along its edge with a plurality of predeterminedly-spaced integral laterally-overhanging projections, having ruling characters thereon adapted to print inclosed spaces for other printed matter. 40

2. A tabular printing form comprising two complementary slugs, one formed with type characters, and the other with a plurality of overhanging projections formed with ruling characters and extending across 45 and seated upon the type-character slug.

3. A tabular printing form comprising a main type-character slug and a separate co-operating tabular slug, the latter being formed with projections having transverse 50 overhanging ruling characters which extend between the type characters on the former.

4. A slug formed with a body portion and an overhanging printing portion, the said overhanging portion being reinforced by an 55 element projecting from the side of the slug and below the edge thereof.

In testimony whereof I hereunto set my hand this twenty fourth day of April, 1912, in the presence of two attesting witnesses.

FERGUS F. WILSON.
